UNITED STATES PATENT OFFICE.

VERNE E. MINICH, OF SCARSDALE, NEW YORK, ASSIGNOR TO THE AMERICAN FOUNDRY EQUIPMENT COMPANY, OF NEW YORK, N. Y., A CORPORATION OF DELAWARE.

SAND-TREATING MACHINE.

Application filed April 6, 1927. Serial No. 181,340.

This invention relates to sand treating apparatus, and more particularly, to a machine for cutting, screening and piling sand to prepare the same for use in foundries.

5 The invention relates more specifically to a machine of the above character, which is adapted to be moved over the floor of a foundry and to cut or disintegrate the sand or other loose material which may be on said floor. After being cut by the machine, the material is propelled upwardly and outwardly and may either be passed through a screen for separating the fine particles from the coarser substances, or may be directed 10 into a pile at the rear of the machine. If the machine is constantly moved in a forward direction the pile of sand will be elongated to form a row, from which workmen may remove the material for subsequent 15 operations.

The cutting, screening and piling machine is preferably of the self-propelled type, mounted upon a chassis having suitable running wheels. An operator may be seated 20 on the chassis and control the movement of the machine over the floor of the foundry for the purpose of re-conditioning sand which has previously been used in molds and leaving the same in proper condition 25 for use in carrying on further foundry operations.

The invention further relates to an adjustable screen and cutting cylinder attached to a machine of the above character, and 30 adapted to be adjusted at the will of the operator into either operative or in-operative position. Both the screen and cutting blade are independently mounted for pivotal movement, and may be hoisted by a reel or other suitable means.

The invention further comprises a piling shroud that is attached to the screen and adapted to direct abrasive material which is picked up by the cutting knives against 45 the screen. A vibrating mechanism may also be included for imparting a shaking movement to the screen for facilitating the separation of the fine and coarse particles.

Although the novel features which are 50 believed to be characteristic of this invention will be particularly pointed out in the claims appended hereto, the invention itself, as to its objects and advantages, the mode of its operation and the manner of its organization may be better understood by referring

to the following description taken in connection with the accompanying drawings forming a part thereof, in which:

Fig. 1 is a side elevation of a cutting, screening and piling machine constructed in accordance with this invention;

Fig. 2 is an elevation of the screening and cutting mechanism in operative position; and

Fig. 3 is an elevation of the screening and cutting mechanism in raised position.

Like reference characters denote like parts in the several figures of the drawings.

In the following description and in the claims parts will be identified by specific 70 names for convenience, but they are intended to be as generic in their application to similar parts as the art will permit.

Referring to the drawings more in detail, the invention is shown as applied to a machine of the above character, comprising a suitable framework or chassis 10, which is mounted upon running wheels 11 to enable the same to be moved back and forth over a foundry floor. A suitable prime mover such 80 as a gasoline motor (not shown) may be mounted upon the framework 10, and enclosed, if desired, by a hood 12, in the usual manner. A radiator 13 may be mounted on the front of the machine to facilitate cooling 85 of the motor, the radiator being adapted to cool the motor either by air or water depending upon the design thereof.

The prime mover may be operatively connected to the driving mechanism for impelling the machine, and also to the series of reels to be hereinafter described, which may be utilized in raising and lowering the piling screen and the cutting blades. A seat 14 for the operator of the machine may be mounted 95 on the frame 10, if desired, various control levers being arranged in readily accessible positions with respect thereto.

The particular type of prime mover and controls employed form no part of the present invention, and consequently will not be described in detail. Any suitable type of mechanism, such as is well known in the foundry art, may be employed for this purpose.

A cutting cylinder 20 provided with a series of cutting blades (not shown) may be pivotally mounted at the rear of the frame, in such manner that it may contact with the floor and the loose material thereon such 110

as sand when in operative position, or may be raised into inoperative position when the machine is to be moved from place to place. Suitable mechanism and connecting means 5 may be provided for driving the cutting cylinder 20, said means preferably being under the control of the operator, whereby they may be connected or disconnected at will. The particular type of connecting means, 10 however, forms no part of the present invention, but is well known in the art and consequently will not be described in detail.

A screen 30 may be mounted at the rear of the cutting cylinder 20, and normally positioned in the line of projection of the material treated by said cylinder. The screen may, however, be pivotally mounted and raised by means of a suitable hoist into inoperative position whereby the free passage 15 of the material being treated is not interfered with, and the same may be allowed to form a pile or row in back of the machine.

Attached to the frame 10 may be a series of vertical and horizontal members to provide 20 suitable supporting means for the above mentioned cutting cylinder and screen, and for the various controls for operating the same.

Cylinder 20 may be journalled for movement in a suitable bearing 21 carried upon radial bar 22, said bar being journalled for pivotal movement about the rod 23 which is attached to the frame of the machine in any suitable manner. Arcuate member 24 30 may be secured to radial member 22, and provided with a peripheral groove to permit the insertion of hoisting cable 25. Cable 25 after passing around member 24 may be connected to reeling mechanism 26, which is carried by the frame of the machine and operated by the prime mover carried thereby. Suitable control mechanism may be included for connecting and disconnecting reel 26 from the source of power whereby, when 40 the same is connected, cable 25 will be reeled up, causing pivotal movement of bar 22 and cylinder 20 connected thereto, about rod 23 into the position shown in Fig. 3.

Piling screen 30 may be mounted upon 50 radial arm 31 which is pivotally attached to frame 10 by a suitable bearing 32. Rod 33 may connect the center portion of screen 30 with arm 31, and may provide for slight pivotal movement of said screen when the same is vibrated, as hereinafter described. Piling shroud 34 and base plate 35 may be rigidly attached at the lower portion of arm 31, wheel 36 being connected to said rod and extending below said base plate to provide 55 a support therefor and for the screen when the same is in lowered position.

The lower portion of screen 30 may be pivotally connected to vibrating rod 37, said rod being fulcrumed upon a support 38 60 rigidly connected to base plate 35 and to

radial arm 31. A suitable lug 38^a may be connected to the end of vibrating arm 37 and positioned to contact with the cam surface 39 carried by cutting cylinder 20. When cylinder 20 is rotated, cam 39 is adapted to co-operate with lug 38^a and by causing a vertical movement thereof, to impart vibrations to screen 30.

The screen assembly may be raised to inoperative position by means of cable 40 75 which may be connected to radial arm 31 and passed over pulley 41 onto reeling drum 42. Reeling drum 42 may be operated by the prime mover by any suitable means under the control of the operator. When power 80 is applied to reeling drum 42, the entire screen assembly will be rotated about bearing 32 into the position shown in Fig. 3. If the cutting cylinder is then operated the sand may be thrown directly onto a pile, or 85 if the cutting cylinder should also be raised to inoperative position the machine may be freely moved without disturbing loose material over which it may pass.

In the operation of the above described 90 machine for the purpose of cutting and screening sand, both cutting cylinder 20 and screen 30 may be placed in lowered position, as shown in Figs. 1 and 2, and the machine moved over the surface to be cleaned or acted 95 upon while power is applied to the cutting blades. These blades in rotating will then act upon the loose sand or other similar material, cutting the same and dividing it into small particles, in which condition it may be 100 propelled by said blades against screen 30. The fine material will then pass through screen 30 and be deposited upon the floor, whereas the coarse particles will be retained and fall into the lower portion of the screen, 105 from whence they may be subsequently removed. As the cutting cylinder is rotated, a vibrating movement will be imparted to the screen by means of cam 39 and lever 37 for facilitating the screening action, and for 110 more completely separating the coarse and fine particles.

Should it be desired to merely cut the sand and to purify the same by aeration without screening, the screen may be raised by means 115 of hoisting drum 42 to the position shown in Fig. 3, while the cutting cylinder 20 may remain in operative position. When the machine is then passed over the floor the cutting blades will pick up the sand, and after agitating the particles will throw them through the air into a windrow at the rear of the machine, the extent of the pile depending upon the quantity of material handled.

The machine may be freely moved without treating the material by raising both cutting cylinder 20 and screen 30 to the position shown in Fig. 3, whereby they are entirely removed from contact with the 120

floor and prevented from acting upon material carried thereby.

This invention provides a simple and practical method of selectively and quickly raising either the cutting cylinder or the piling screen into inoperative position without the employment of expensive mounting or complicated mechanism. The reeling drums for the screen and cylinder may be readily operated by the prime mover of the machine, and the controls therefor placed in accessible positions whereby they may be instantly available to the operator of the machine.

15 In the drawings accompanying and forming part of this specification, a practical commercial embodiment of the invention is disclosed, but as such illustration is primarily for purposes of disclosure, it will be understood that the structure may be modified in various respects without departure from the broad spirit and scope of the invention as hereinafter defined and claimed.

What is claimed is:

25 1. A cutting, screening and piling machine comprising a framework mounted upon wheels for movement over a floor, a prime mover carried by said framework for propelling the same, a cutting cylinder 30 mounted for rotational and transverse movement with respect to said framework, a hoisting cable for controlling the transverse position of said cylinder with respect to said framework, a screen pivotally mounted at the rear of said cutting cylinder and adapted 35 to receive material impelled from said cylinder, a shroud for directing said material against said screen, a hoisting cable for controlling the position of said screen, and means for vibrating said screen.

2. A cutting, screening and piling machine comprising a framework mounted upon wheels for movement over a floor, a prime mover carried by said framework for propelling the same, a radial arm pivotally connected at the rear thereof, a cutting cylinder mounted for rotational movement on said radial arm, a hoisting cable attached to said arm for controlling the position of said cylinder with respect to said framework, a screen pivotally mounted at the rear of said cutting cylinder and adapted to receive material impelled from said cylinder, a shroud for directing said material against said screen, a hoisting cable for controlling the position of said screen, and means including a cam surface for vibrating said screen.

3. A cutting, screening and piling machine comprising a framework mounted upon wheels for movement over a floor, a prime mover carried by said framework for propelling the same, a radial arm pivotally connected at the rear thereof, a cutting cylinder mounted for rotational movement on said radial arm, an arcuate member attached to

said arm, a hoisting cable passing around the periphery of said arcuate member for controlling the position of said cylinder with respect to said framework, a screen pivotally mounted at the rear of said cutting cylinder and adapted to receive material impelled from said cylinder, a hoisting cable for controlling the position of said screen, and means carried by said screen and including a cam surface for vibrating said screen. 70 75

4. A cutting, screening and piling machine comprising a framework mounted upon wheels for movement over a floor, a prime mover carried by said framework for propelling the same, a radial arm pivotally connected at the rear thereof, a cutting cylinder mounted for rotational movement on said radial arm, an arcuate member attached to said arm, a hoisting cable passing around the periphery of said arcuate member for controlling the position of said cylinder with respect to said framework, a reeling drum, means for connecting said hoisting cable to said reeling drum, and means operatively connecting said reeling drum to said prime mover for controlling the position of said cylinder, a screen pivotally mounted at the rear of said cutting cylinder and adapted to receive material impelled from said cylinder, a shroud for directing 80 85 90 said material against said screen, a hoisting cable for controlling the position of said screen, and a member carried by said screen and co-operating with a cam surface for vibrating said screen.

5. A cutting, screening and piling machine comprising a framework mounted upon wheels for movement over a floor, a prime mover carried by said framework for propelling the same, a cutting cylinder 105 mounted for rotational and transverse movement with respect to said framework, a hoisting cable for controlling the transverse position of said cylinder with respect to said framework, a screen, means for mounting said screen at the rear of said cutting cylinder comprising a radial rod pivotally connected to said framework and loosely connected to said screen, a shroud for directing material against said screen, a hoisting cable for controlling the position of said screen, and means including a cam surface for vibrating said screen. 110 115

6. A cutting, screening and piling machine comprising a framework mounted upon wheels for movement over a floor, a prime mover carried by said framework for propelling the same, a cutting cylinder mounted for rotational and transverse movement with respect to said framework, a hoisting cable for controlling the transverse position of said cylinder with respect to said framework, a screen, means for mounting said screen at the rear of said cutting cylinder comprising a radial rod pivotally con- 120 125 130

nected to said framework and loosely connected to said screen, a shroud for directing material against said screen, a hoisting cable attached to said radial rod, a winding drum for reeling said cable, said drum being operatively connected to said prime mover, and means for vibrating said screen.

7. A cutting, screening and piling machine comprising a framework mounted upon wheels for movement over a floor, a prime mover carried by said framework for propelling the same, a radial arm pivotally connected at the rear thereof, a cutting cylinder mounted for rotational movement on said radial arm, an arcuate member attached to said arm, a hoisting cable passing around the periphery of said arcuate member for controlling the position of said cylinder with respect to said framework, a reeling drum, means for connecting said hoisting cable to said reeling drum, and means operatively connecting said reeling drum to said prime mover for controlling the position of said cylinder, a screen, means for mounting said screen at the rear of said cutting cylinder comprising a radial rod pivotally connected to said framework and loosely connected to said screen, a shroud for directing material against said screen, a hoisting cable attached to said radial rod, a winding drum for reeling said cable, said drum being operatively connected to said mover, a vibrating rod attached to said screen, a lug mounted on the free end of said member, and a cam carried by said cutting cylinder and co-operating with said lug whereby rotation of said cylinder is utilized for imparting vibrations to said screen.

8. A cutting, screening and piling machine comprising a framework mounted upon wheels for movement over a floor, a prime mover carried by said framework for propelling the same, a radial arm pivotally connected at the rear thereof, a cutting cylinder mounted for rotational movement on said radial arm, an arcuate member attached to said arm, a hoisting cable passing around the periphery of said arcuate member for controlling the position of said cylinder with respect to said framework, a reeling drum, means for connecting said hoisting cable to said reeling drum, and means operatively connecting said reeling drum to said prime mover for controlling the position of said cylinder, a screen, means for mounting said screen at the rear of said cutting cylinder comprising a radial rod pivotally connected to said framework and loosely connected to said screen, a shroud for directing material against said screen, a hoisting cable attached to said radial rod, a winding drum for reeling said cable, said drum being operatively connected to said mover, a vibrating rod attached to said screen, a lug mounted on the free end of said member, and a cam carried by said cutting cylinder and co-operating with said lug whereby rotation of said cylinder is utilized for imparting vibrations to said screen.

In testimony whereof I have hereunto set my hand.

VERNE E. MINICH.
